TAPPET

Webster D. Corlett, Oak Park, Ill., assignor to
 Standard Screw Company, Hartford, Conn., a
 corporation of New Jersey

Application October 5, 1932, Serial No. 636,412

4 Claims. (Cl. 123—90)

This invention relates to a valve tappet and to similar articles and has for one object to provide a valve tappet formed of a single piece, in which the head may be chilled to have satisfactory wearing qualities and in which the remainder of the tappet is formed integrally with the head in a single operation. Another object is to provide a valve tappet or similar member which is hollow and which has sufficient structural strength, and in which the wearing head and the portion of the tappet which is attached to any other part, as well as the body of the tappet, are all formed integrally. Another object is to make a valve tappet of such shape that it will be, in its normal operation, readily and certainly lubricated. Another object is to form a tappet in which the body diameter is the same as, or larger than, that of the hardened cam-contacting head, as distinguished from the common mushroom type of tappet.

Other objects will appear from time to time in the specification and claims.

My invention is illustrated more or less diagrammatically in the accompanying drawing, 25 wherein—

Figure 1 is a diagrammatic sectional view, showing a tappet in position in an engine;

Figure 2 is a longitudinal cross section of the tappet, taken at line 2—2 of Figure 1;

Figure 3 is a transverse section taken at line 3—3 of Figure 2;

Figure 4 is a section similar to Figure 2, showing a modified form;

Figure 5 is a transverse section taken at line 5—5 of Figure 4;

Figure 6 is a plan view, showing one part of a mold in plan, with the complete pattern in position within the mold;

Like parts are designated by like characters throughout the specification and drawing.

A is a tappet guide of any suitable form, perforated as at A¹.

B is a cam which may be of any suitable design and is rotated so as to move the tappet. It is in contact with the lower or working face of the tappet.

The tappet is formed of a generally cylindrical body C, ported as at C¹ and provided with a closed end C² which provides a working face with which the cam is in contact. At its opposite end the generally cylindrical tappet is provided with a closure or end portion C⁴ which is provided with an integrally threaded opening or perforation C⁵. About the perforation C⁵ there is a reduced extension or neck C⁶. For purposes

of strength, one or more circumferential ribs C⁷ may be formed about the interior of the tappet, as shown for example in Figures 2 to 5, inclusive. For some purposes it is desirable to add one or more longitudinal ribs C⁸. These are shown in the form of the device appearing in Figures 2 and 3, in which the circumferential rib C⁷ is also shown. The tappet may have seated at its threaded end C⁵ any form of attachment, indicated generally as at D, which may contact a 10 push rod, valve stem or any other member, indicated diagrammatically at D¹ in Figure 1. The details of these parts or of other parts which might be attached to the tappet form no essential part of the present invention and will not be 15 further described.

While the tappet of this invention might be formed in any suitable manner, it is economical to cast it as a single piece, in a single operation, so that the tappet shown in Figures 1 to 5, 20 inclusive, is cast as a unit. One form of mold is indicated in plan in Figure 6. As there shown, a cast iron chill place E is arranged so that it will contact the end faces or heads C² of the tappet when the latter is cast. A "green sand" mold F 25 is formed in any suitable contour or in any suitable manner, and is provided with a gate F¹ having branches F² communicating with the individual tappet molds, by means of which metal may flow to form the individual tappets. A pattern of 30 suitable form is first made and this may be made to form a single tappet or a number, as shown in the drawing. In any event, it is used to shape the sand to form one or more tappet cavities F³.

After the mold has been so shaped, a core which 35 has been separately made is inserted in the tappet cavities. As shown the core is multiple, to be used in making a number of tappets simultaneously. It comprises the rounded portions G, provided with circular grooves G¹ to form the circumferential ribs C⁷, and with protruding portions G² G³, to form the ports C¹ on one side of each of the tappets, and the members G² also serve to join together the several portions G. Shorter extending members G³ are formed on 45 each of the members G and these serve to form the other ports C¹. After the two parts of the sand mold have been formed with the tappet cavities and with portions to receive the core and particularly to receive the members G² of the core, 50 the latter is put in place in one part of the mold. The other part of the mold is then secured in place and the metal may be poured. When it is hard, the mold is removed, the cores are broken up and fall out or are removed from the tappet 55

castings which are then finished and may be thereafter drilled and tapped to provide the threaded perforations C⁵.

It will be realized that whereas I have herewith shown and described a practical operative device, nevertheless many changes might be made in the size, shape, and number and disposition of parts, without departing from the spirit of my invention, and I wish, therefore, that my showing be taken 10 as in a sense diagrammatic.

In particular the tappet may be used without tapping the upper end to receive an adjusting screw or other attaching part. It may be so made that the upper end is closed and treated to receive the thrust end of a valve or push rod. Such 15 an arrangement is useful in connection with non-adjustable tappets.

The construction of the tappet above described provides a greater strength on the cam contacting face by reason of the support which the cylindrical body portion gives to the edges of the cam face. The cylindrical body portion being larger than the shaft portion of the ordinary mushroom type of tappet, has a greater bearing 20 surface than the mushroom type and the tapped hole in which the tappet is connected to another part is larger than would be the case with the mushroom type, by reason of the greater section due to the enlarged cylindrical body. Because 25 the diameter of the head is the same as that of the cylindrical body, the tappet can be removed from the motor block without removing the cam shaft.

The provision of ports provides for lightness, 30 reducing the mass of metal and consequently the weight of the tappet. It also provides for lubrication, as lubricant will be splashed into and will otherwise reach the interior of the tappet and since the tappet is made in a single piece instead of built up in a plurality of pieces, the cost is 35 reduced and danger of coming apart or separation which occurs in a built-up tappet is eliminated.

The use and operation of my invention are as 40 follows:

When the tappet of this invention is used, it will 45 have been made in the proper size and will be inserted in an engine. The working end or face is positioned so as to be in contact with or actuated by a cam and its other end is connected in any 50 suitable manner with a valve, a push rod, or any other mechanism desired. In the form shown, the end of the tappet away from the working face is provided with a threaded perforation or depression 55 and into this may be seated a push rod, a valve stem or any other connection or connecting member that is desirable. In the engine operation, the tappet is moved by the cam and when the cam face recedes, it returns, following the cam in 60 and out. As it moves outward, the lower portions 65 of the ports are exposed below the guide and lubrication enters the ports. As the tappet moves in or up again, so that the ports are closed by the guide, the lubricant within the hollow tappet is moved about and splashes out more or less through any and all of the ports and so lubricates the tappet and guide and thus provides a more adequate degree of lubrication for the tappet than is 70 possible with a solid tappet. The parts may be so proportioned that the upper ports are uncovered during the extreme inner movement of the tappet, so that in some cases both the upper and lower ports will be alternately uncovered and covered and while uncovered, lubricant will enter 75 them and provide the lubrication just mentioned.

Circulation of air also occurs through the ports and through the hollow tappet so that an additional cooling effect is provided.

In tappets which have heads larger than the body of the tappet, in the case of breakage, the 5 tappet cannot be removed except by removing the cam shaft and then dropping the tappets out. In the tappet of this invention, since the head is no larger than the body, in case for any reason it is necessary to remove the tappets, they may be 10 moved by merely pulling them out away from the cam shaft and it is not necessary, therefore, to take down the engine or to move or remove the cam shaft or cams.

Where tappets are made with enlarged heads, 15 breakage most frequently occurs at or near the edges of the enlarged head. This is due to the fact that the edges are thinned and unsupported. In the tappet of the present invention, since the head is not enlarged and since its diameter is 20 the same as the outer diameter of the cylinder portion of the tappet, the outer edges of the head are completely supported by the cylindrical body, and the head is thus stronger and less liable to breakage than would be the case where the edges 25 of the head are unsupported as in the typical tappet in which the head is larger than the shaft.

The operation of forming the tappets which 30 permits the making of an inexpensive, strong, unitary tappet, in one form of the invention involves the casting of these tappets either singly or in groups. The steps of casting are essentially 35 the same, whether one tappet, or more, is made at a time. A pattern is made, either for a single tappet or for several, and the pattern is so shaped 40 as to provide in the mold not merely the cavity for the casting of the tappet but to provide also spaces or cavities to hold a core by means of which the hollow interior and the ports of the tappet may be formed. In ordinary practice the 45 mold is a "green sand" mold. In this the tappet cavity is formed by the pattern or patterns and then the cores, which may be of any suitable design or material, are put in place and the metal 50 is cast. As shown in Figure 6, a cast iron chill plate is used so that the working faces or heads 55 of the tappets may be properly chilled. After the metal has been cast, it is taken out of the sand, the cores are broken up and the portion of the core which lies within each tappet is extracted or discharged through the ports.

Thus the tappet itself is so designed that in 60 casting it a core may be supported within it throughout the side ports and these ports thus serve the purpose of lightening the tappet, providing better lubrication for the side walls and permitting the support of the core during casting and its removal thereafter. In the particular 65 method of manufacture illustrated, the tappet is cast on its side, with a continuous core serving all tappets on one side of the mold, and a chill plate is provided to chill the cam-contacting faces. What might be called the "side ports" in the tappets are formed by the connecting link 70 portions G² of the continuous core, and the upper and lower ports may be formed by the core or by the mold.

The invention is not necessarily limited to the 75 particular method of forming the tappet above outlined and illustrated in the drawing. The method of casting is a satisfactory and economical method of forming the tappet and it is described herein for a better understanding of the device, but the invention is not limited to it and the 80

steps of the method of forming it are not claimed in the present case.

I claim:

1. A valve tappet for engines comprising a hollow cylindrical member closed at each end and means for raising lubricant by said tappet, said means comprising the closure for one end of said tappet, the cylindrical wall being relatively thin and integrally united with the substantially thicker end walls, said cylindrical wall being provided with a plurality of relatively large cooling and lubricating apertures extending therethrough, the apertures being disposed in substantially diametrically opposed pairs, there being at least one pair of said apertures adjacent to each end wall of the tappet, the apertures adjacent opposite ends of the tappet being in free communication with each other through the hollow interior of the tappet.
  2. A valve tappet for engines comprising a hollow, cylindrical substantially cage-like body having end walls of substantial thickness, the cylindrical walls of the body being relatively thin and provided with a plurality of relatively large perforations separated by relatively narrow bridges of metal, the lower end of the tappet being closed by a lubricant carrying bottom member, the upper end of the tappet being also substantially closed.
  3. In a valve tappet for engines, means for cooling and lubricating said tappet, and means for raising, retaining and discharging lubricant from said tappet, comprising a hollow cylindrical wall member, a closure for one end of said member,
- 5 10 15 20 25 30
- said closure comprising a relatively thickened wall and being provided on its outside with a surface suitable for contact with a tappet operating means, the diameter of said closure being the same as the outside diameter of said cylindrical wall, the cylindrical wall being formed of relatively thin material integrally united at its edges with said closure and being provided with a plurality of freely open ports, some ports being adjacent each end of the wall, said closure comprising said lubricant raising member and the cylindrical wall comprising said lubricant retaining member.
4. In combination, a tappet and a tappet guide, the tappet including lubricant raising and distributing means, and a cylindrical wall, freely ported and being closed at its lower end by a thickened member which comprises said lubricant raising means and is provided on its outside with a surface suitable for contact with a tappet operating means, the outside diameter of the closing member and of the cylinder being the same, the cylinder being freely ported with ports adjacent its top and bottom, the proportions of the guide and tappet being such that in the lower position of the tappet a lower port is uncovered and in the upper position of the tappet an upper port is uncovered, whereby free lubricant and air circulation into and through the body of the tappet is provided, the cylindrical wall co-operating with said closure member to retain lubricant upon the end closure.
- 10 15 20 25 30

WEBSTER D. CORLETT.
